(57) **CLAIM**

The ornamental design for a pet harness, as shown and described.

DESCRIPTION

FIG. 1 is a top plan view of a pet harness showing my new design;

FIG. 2 is a front elevational view thereof;

FIG. 3 is a bottom plan view thereof;

FIG. 4 is a side elevational view from the right of FIG. 1;

FIG. 5 is a rear elevational view thereof;

FIG. 6 is a side elevational view from the left of FIG. 1;

FIG. 7 is a right side elevational view shown in use;

FIG. 8 is a front elevational view shown in use; and,

FIG. 9 is a front elevational view shown in use, the broken lines are for illustrative purposes only and form no part of the claimed design.
